UNITED STATES PATENT OFFICE.

CLAYTON C. ANDREWS, OF WATERBURY, CONNECTICUT, ASSIGNOR TO THE AMERICAN RING COMPANY, OF SAME PLACE.

SHEET-METAL RING AND METHOD OF MAKING THE SAME.

SPECIFICATION forming part of Letters Patent No. 357,302, dated February 8, 1887.

Application filed November 15, 1886. Serial No. 218,967. (No model.)

To all whom it may concern:

Be it known that I, CLAYTON C. ANDREWS, of Waterbury, in the county of New Haven and State of Connecticut, have invented an improvement in Sheet-Metal Rings, of which the following is a specification.

Figures 1 and 2 are partial sections in larger size of well-known forms of rings. Figs. 3 and 4 are partial sections showing my improvements, also in larger size; and Fig. 5 is a section of my improved ring.

Hollow rings for cornices, &c., have been made out of a ring-shaped blank of sheet metal drawn up in dies, so that the metal of the inner part of the ring comes inside the metal of the outer part of the ring, as seen sectionally in larger size in Fig. 1; but in this case the outer edge of the flat sheet-metal blank, being of greater length than the same edge of the sheet metal after it has been stamped up into the form of the hollow ring, such edge (2) is liable to be corrugated and thickened, and the ring does not have a finished appearance, and it is liable to be rough and to scratch the cornice-pole. In some instances the edges of the sheet metal have been brought together as shown in Fig. 2; but there is nothing to strengthen the metal at the joint, and it is liable to become dented and injured in use.

My invention is for strengthening the sheet metal of the ring at the joint and rendering the inside smooth and at the same time facilitating the construction.

The sheet-metal blank is cut out in the form of a ring and stamped up in dies, as usual, until it assumes the form of a hollow blank or shell. (Shown sectionally in large size in Fig. 3.) At this stage it may be annealed, if necessary, and cleaned by acid. The edge 3 is then rolled over inwardly by a suitable die, so as to form a bead, 4, having a semicircular

or greater sectional contour, as seen in Fig. 4. This rib is made of the portion of the sheet metal that is slightly thickened in pressing up from the flat blank; hence this bead is 45 the strongest part of the ring. The inner edge 5, of the sheet-metal blank is outside this rib 4, and it is closed firmly against such rib, and thereby bent outwardly, so that the inner part of the ring that comes into contact with 50 the cornice-pole is convex sectionally and smooth, and the pole does not become scratched. Besides this, the pressure can be sufficiently hard to impact the metallic surfaces together and render them water-tight, or nearly so, and the acid or liquid will not pass into the hollow ring in any subsequent dipping, plating, or coloring operation, and the ring is smooth and much stronger than the rings heretofore made.

I claim as my invention—

1. The method herein specified of making hollow sheet-metal cornice or other rings, consisting in cutting out the ring-shaped blank, pressing the same up into a hollow blank or 65 shell of a U-shaped section, and then rolling the outer edge of the sheet-metal inwardly and downwardly to form a rib within the inner edge of the sheet metal, and then pressing such inner edge outwardly against the rib, 70 substantially as set forth.

2. The hollow sheet-metal ring having the inwardly-turned rib 4 within the inner edge of the sheet metal, the latter being bent outwardly against the rib, substantially as set 75 forth.

Signed by me this 10th day of November, A. D. 1886.

CLAYTON C. ANDREWS.
